UNITED STATES PATENT OFFICE.

ALBERT C. BECKEN, OF CHICAGO, ILLINOIS.

BRACELET-HOLDER FOR WATCHES.

1,093,757.

Specification of Letters Patent   Patented Apr. 21, 1914.

Application filed June 23, 1913. Serial No. 775,837.

To all whom it may concern:

Be it known that I, ALBERT C. BECKEN, a citizen of the United States of America, and a resident of Chicago, county of Cook, 5 and State of Illinois, have invented certain new and useful Improvements in Bracelet-Holders for Watches, of which the following is a specification.

My invention relates to bracelet holders 10 for watches, lockets and similar devices, and has for its object improvements in such devices.

Bracelet holders consist of two classes, first, those in the nature of an elastic band 15 and which are slipped over the hand, and second, those which do not slip over the hand but are fastened around the wrist by connecting together separable ends of the bracelet. It is obvious that in the second 20 class of devices, the person who secures the bracelet on his own wrist has but one hand which he can use for the operation.

The present device is arranged so as to facilitate the placing of the bracelet on the 25 wrist by the use of only one hand.

In the accompanying drawings Figure 1 illustrates the manner of placing the bracelet upon the wrist; Fig. 2 is a side elevation of the bracelet; and Fig. 3 is a trans- 30 verse section on line 3—3 of Fig. 2.

The watch or locket holder H is made of leather or other suitable material and is provided with ears E through which passes a strap S having a buckle B on one end. 35 The other end of the strap is provided with holes, as shown in Fig. 1, for engagement with the tongue of the buckle in the ordinary manner. On account of the pliability of the strap S there has heretofore been 40 much difficulty in applying such holders to the wrist by the use of only one hand, and many persons have refused to purchase such holders, or have failed to use them after purchasing them because of this difficulty. 45 I overcome the objections to this type of bracelet holders by adding thereto a flat steel spring A which is held in place by a lining L cemented or sewed to the strap as shown in Fig. 3. The length of this spring 50 is preferably a little more than one-half the circumference of the normal wrist and

extends from the buckle B to about the point P. This spring is given an initial or preliminary shape which causes it to correspond closely to the upper half of the oval 55 of the wrist and extends to about the line representing the major axis through the wrist below. The normal contour of the spring and its desirable length are illustrated by the curved part of the strap as 60 it appears in Fig. 2.

In applying the bracelet the upper part of the oval, as shown in Fig. 2, is hung upon the wrist in much the same way that a hook is hung upon a beam. In doing this 65 the spring A is slightly flexed, and when the flexing is released the bracelet rests lightly upon and close to the wrist with that part of the strap hanging downward which extends beyond the point P. In this position 70 the operator may pull slightly upon the strap without displacing the bracelet from the wrist, and needs but one hand to push the end of the strap through the buckle as shown in Fig. 1. The buckle, of course, has 75 a certain amount of friction at the point of connection with the strap, and this friction permits the buckle to be adjusted by hand to a position which will be convenient for the insertion of the free end of the strap by 80 one hand only.

What I claim is:—

1. In a bracelet holder for watches, the combination with a holder, a strap, and a buckle for securing the strap and holder 85 to the wrist of the wearer, of a spring secured to the strap and extending in the form of a hook from the buckle to a point beyond the holder and equal in length to more than one-half the circumference of the 90 wrist but less than the entire circumference, said spring serving to normally hold the strap in such form that it may be easily placed upon the wrist by one hand only and also serving to retain the strap in position 95 on the wrist so that the free end of the strap may be inserted in the buckle by one hand only.

2. In a bracelet holder, a holder, a strap secured thereto, a buckle secured to one end 100 of the strap, and a spring secured to the strap and extending from the buckle to the

holder, said spring being bent so that the part of the strap between the buckle and the holder will be held in the form of a hook adapted to engage the wrist and support the 5 buckle in a position convenient for the insertion of the free end of the strap in the buckle by one hand only.

Signed at Chicago, Illinois this 20th day of June 1913.

ALBERT C. BECKEN.
